UNITED STATES PATENT OFFICE.

JOHN S. BRENNAN, OF MILWAUKEE, WISCONSIN.

FABRIC FOR OIL WICKS.

1,403,229.

Specification of Letters Patent. Patented Jan. 10, 1922.

Application filed December 27, 1920. Serial No. 433,394.

To all whom it may concern:

Be it known that I, JOHN S. BRENNAN, a citizen of the United States, and resident of Milwaukee, in the county of Milwaukee and State of Wisconsin, have invented certain new and useful Improvements in Fabrics for Oil Wicks; and I do hereby declare that the following is a full, clear, and exact description thereof.

10 My invention refers to woven asbestos wick strips for oil burners of that general type, described in my Patent No. 1327858, dated January 13th, 1920.

The primary object of my present invention is to provide a woven asbestos wick wherein the strands are reinforced by a wire core, to materially increase the life of the wick, and to render the same of sufficient rigidity, whereby it would maintain its 20 normal shape under high temperatures to which it is subjected under ordinary usage. In wicks of this particular type, practice has demonstrated that in order to form the asbestos strands from which the wick is 25 woven, a certain small percentage of cotton constituting a binder is necessary, due to the fact that pure asbestos fibre is comparatively of short lengths, and hence, for example, a portion of cotton fibre is used approximating 10 or 15%. The result in the use of the cotton, in woven wicks, is that the 30 heat to which the wick is subjected, will result in the partial consumption of the cotton, whereby the wick, as a whole, becomes 35 flabby and has a tendency to contract or sag about its burning edge.

By adding a wire strand in the form of a core to certain or all of the asbestos strands, the above objectionable features are overcome, as the metal core thus forms a rigid backbone, upon which the woven structure is built, and whereby it will maintain its normal shape under long usage.

With the above objects in view, the invention consists in certain peculiarities of construction and combination of parts, as are hereinafter fully set forth with reference to the accompanying drawings and subsequently claimed.

50 In the drawings,

Figure 1 represents a fragmentary side elevation of a wick upon a magnified scale, embodying the features of my invention.

Figure 2 is a diagrammatic plane view of 55 the wick strip showing the same in circular form adapted to be nested about its burner,

it being understood that when the wick is so nested the reinforced ends thereof are lapped, and

Figure 3 is a detail magnified view of one 60 of the asbestos strands from which the wick is woven, the same illustrating the method of manufacturing the strand.

Referring by characters to the drawings, and as best shown in Figure 1, 1 represents 65 a woof and 2 the warp threads of a woven wick strip, which may be of any length and width. In this exemplification of my invention, both the woof and warp strands have central wire cores 3, about which the asbestos fibre which form the strands are fitted. As best shown in Figure 3, the asbestos strands are formed by first twisting threads 2 of the asbestos material in long lengths, and in order to add the strength to the asbestos fibre strand, a small percentage of cotton is mixed with it. After these strands are formed, they are wrapped about the wire core 3, as shown, and thus the woven strands 75 thereafter are utilized to produce a wick 80 strip of the desired length and breadth, as shown in Figure 1. The wick strips are preferably provided with reinforcing end plates 4, which end plates, as shown in Figure 1, are folded over the wick ends and 85 when the wick is inserted over a burner, these metal reinforced ends are preferably lapped one over the other, so as to produce in effect a continuous circular wick. Obviously without departing from the spirit of 90 my invention, I may in some instances weave the wick strips in circular formation, and while I have shown and described both the warp and woof as having metal wire cores, I may in some instances use the wire cores 95 only with the warp strands or vice-versa.

It will also be observed that while I have shown the asbestos thread as wrapped about the core wire to complete the strand, obviously the wire and thread may, in some instances, be coiled about each other in various manners to complete the strand, without departing from the spirit of my invention.

Furthermore, I may without departing 105 from the spirit of my invention substitute, in some instances, material other than asbestos for the strands having reinforcing core wires.

I claim:

1. A wick strip adapted to be fitted about 110 a burner comprising a series of woven as-

- bestos strands each strand having its own wire core.
2. A wick strip adapted to be fitted about a burner, comprising a series of woven asbestos strands, the warp strands being provided with wire cores.
3. As a new article of manufacture, a wick for oil burners comprising a series of interwoven strands each strand being composed of asbestos having wire reinforcing threads.
4. A wick strip for oil burners comprising a series of woven asbestos strands, the strands having a small percentage of cotton therein and a wire thread.
- In testimony that I claim the foregoing ¹⁵ I have hereunto set my hand at Milwaukee, in the county of Milwaukee and State of Wisconsin.

JOHN S. BRENNAN.
